J. P. McCandless
INVENTOR.

UNITED STATES PATENT OFFICE.

JOSEPH P. McCANDLESS, OF NEW YORK, N. Y.

BLANK-BOOK.

SPECIFICATION forming part of Letters Patent No. 295,266, dated March 18, 1884.

Application filed July 5, 1876.

To all whom it may concern:

Be it known that I, JOSEPH P. McCANDLESS, a citizen of the United States, and a resident of the city, county, and State of New York, 5 have invented a new and useful Improvement in Books, of which the following is a full, complete, and exact specification, reference being had to the annexed drawings.

My invention relates to an improvement in 10 books, by means of which the body of the book or the sheets can be adjusted to the cover and removed from the same and a new body supplied as often as necessary.

In the drawings, Figure 1 is a front view of 15 my improved book lying open. Fig. 2 is a sectional view on the line $x-y$ of Fig. 1, the book being still open. Fig. 3 is a sectional view on the line $x-y$, Fig. 1, the book being closed. Fig. 4 shows a front and side view of 20 the U-shaped wire forming the attachment by means of which the body may be connected with or removed from the cover. Fig. 5 shows an end view as well as a transverse sectional view of the same attachment.

25 Similar letters refer to similar parts throughout the drawings.

In the drawings, A indicates the cover, having a flexible joint or back, B.

H indicates the U-shaped wire, which is 30 made of a piece of metal wire bent in the middle, so that one portion shall be parallel to the other, leaving at the bent end H^4 sufficient curvature to insure requisite elasticity to the portion H^6 . The lower arm, H^5 , of the 35 U-shaped wire H terminates as shown in the hook H^2 . The upper arm of the U-shaped wire is indicated by H^6 , and the end of said arm is indicated by H^3 . The knobs or buttons H^4 are only used for the purpose of covering 40 the ends of the wire H and causing them to present a neat appearance.

The sheets of paper used to form the book to the cover of which this U-shaped wire H as constructed is attached are arranged in the 45 following manner: The requisite number of long or open sheets of paper, (indicated by E.) whose length is nearly conformable to that of the cover, are taken and laid out openly over the entire length of the cover. Then above 50 these, on each side, I place any number of short sheets, the sets of which are indicated respectively by C and D. These short sheets

C and D are arranged with their backs toward each other in such a manner as to leave between them a groove or recess, F, for the 55 reception of the upper arm, H^6 , of the U-shaped wire H; or, if preferred, a piece of cloth or other suitable material may be substituted for the set of long sheets E. In this case the cloth would only extend far enough 60 on the sheets C and D to admit of fastening it to the latter. The recess F is covered with cloth, canvas, or other suitable material, G, the edges of which are fastened to the ends of the sets C and D at C' and D' by any suitable 65 means, preferably by pasting. The object of this piece of canvas is to prevent the wire H from cutting or wearing out the sheets forming the set E, which would result from the frequent opening and closing of the book. 70 These short sheets of paper C and D are secured to the set E by means of fasteners, which are driven through the sheets at C' and D' from one side and clinched on the other; or the sheets may be sewed together. This arrangement of 75 the body or the sheets of the book enables me to construct my book in such a manner as to include in the same body sheets devoted to entirely different purposes—for instance, one set 80 of sheets C may be a memorandum account and the set of sheets D may be a cash account, and vice versa. The U-shaped wire H is secured to the back or flexible joint B by placing on said back the lower arm, H^5 , of said wire and covering the same completely with a piece 85 of canvas or leather, B, with the exception of the hook H^2 , which projects through and above the material, and securing the same to the back by pasting it over the back and a portion of each side of the cover. The body of the book 90 is thus adjusted to the cover A. The body, as above constructed, is placed on the cover, so that the upper arm, H^6 , of the U-shaped wire shall fall in the recess F, when the body is secured by placing the end H^3 of the arm 95 H^6 in the hook H^2 .

The advantage which results from the use of this U-shaped wire, as well as from this method of constructing the body of the book, is that the body or the sheets of the book may 100 be removed and a new one substituted in its place when the former shall have been used; and, again, the body of the book is not liable to displacement when most of the leaves have

been torn out at the perforations indicated by I. Neither has the body of the book any tendency to spring open at the middle, which will happen when a wire or rubber band is used without the recess F.

What I claim as new, and desire to secure by Letters Patent, is—

1. The combination of the open sheets E and the short sheets C and D, provided with to the recess F, substantially in the manner described and set forth.
2. In a book, the combination of the cover

A, having attached to its flexible joint or back B the U-shaped wire H, constructed as described, the open sheets E, and the short sheets C and D, arranged and operating all in the manner described, and for the purposes set forth. 15

3. In a book, the combination of the cover A with the U-shaped wire H, constructed substantially as described and set forth:

J. P. McCANDLESS.
